UNITED STATES PATENT OFFICE.

THOMAS M. K. OVERLAND, OF NEW BRIGHTON, NEW YORK.

TRACK CONSTRUCTION FOR UNDERGROUND RAILWAYS AND TUNNELS.

No. 859,330.

Specification of Letters Patent.

Patented July 9, 1907.

Application filed March 12, 1907. Serial No. 361,977.

To all whom it may concern:

Be it known that I, THOMAS M. K. OVERLAND, a subject of the King of Norway, and a resident of New Brighton, S. I., in the county of Richmond and State 5 of New York, have invented certain new and useful Improvements in Track Construction for Underground Railways and Tunnels, of which the following is a specification.

My invention relates to improvements in track construction for railways having a solid and rigid roadbed of concrete or a material of similar character as the case is with some street railways, subrailways, ordinary and subaqueous tunnels, and the object is to give the rails a permanent location both as to alignment and level, in this way reducing the cost of adjustment of tracks and securing a permanent clearance between cars and the inner face of the tunnel, further to reduce the height or diameter respectively of tunnels, decrease the noise and jolting of cars, facilitate the cleaning of the tunnel floor and walking along the track and render the construction as far as possible fireproof.

Figure 1 is a cross section of the rail and its foundation; Fig. 3 is a cross section in a smaller scale of one track showing the entire tunnel floor; and Fig. 2 is a longitudinal section on line 1—2 in Fig. 3.

Similar letters refer to similar parts throughout the several views.

Two longitudinal steel ties (rail channels) C—one 30 for each rail—of a built up or rolled section in the general shape of a channel or trough are embedded in the concrete floor A.

B is a cement grouting applied in one of the ways now in practice for securing a reliable connection between the concrete floor already in place and the bottom plate of the rail channel. In this rail channel are laid down wooden blocks (join-timber) E of such size that about 1/4" to 1/2" wide spaces are left between the join-timber and the inner face of the rail channels as well as between the separate wooden blocks. The join-timber is laid crosswise to the rail as shown on the drawing; it may also be laid lengthwise and in longer pieces. The join-timber being carefully surfaced, a filling D is poured into the narrow space surrounding it as well as in between the individual blocks. When the filling has hardened the rails are fastened to the join-timber by means of screws or otherwise. The function of the rail channel is to distribute the wheel action lengthwise as well as laterally 50 to the concrete floor.

The rail channels are on the drawing, see Fig. 1, made up of two special bulb angles and one bottom plate. It also can be made up of two rolled channels and a bottom plate—the flanges of the rolled channels

pointing out from the rail and the lower one riveted 55 to the extended bottom plate—or it can be made up of two Z bars and a bottom plate, the upper flanges of the Z bars pointing out from the rail and the lower ones riveted to the bottom plate. A vital point in this combination is the filling or casting around the join-timber. A compound of asphalt is one of the best materials now in the market; it is practically waterproof, fireproof and a non-conductor of electricity; the last mentioned quality is of importance for electric railways. At temperatures between +100° F. and 0° F. 60 it possesses the necessary strength and elasticity, flows freely at +425° F. and in about 1/2" thick layers it will harden in less than 20 minutes.

Rails supported by cross ties at distances of about 2 feet resemble somewhat strings on a musical instrument and on account of their discontinued support are a source of noise, impacts, and wear and tear on all parts of the railroad material. Therefore one of the points in this invention is the realization of an exact and permanent surfacing of the rail bearings (the join-timber) and a consequent giving the rails a continuous and rigid bearing on every linear inch of their length. This will provide for smoothly running of cars, decrease the noise and consequently benefit the nerves of the passengers as well as preserve the railroad material.

(The impacts of wheels being reduced and more distributed is of special value in cast iron tunnels.)

The very useful transition curve with its varying superelevation can now be fully realized and even permanently maintained, which means increased safety 85 as well as economy.

The tunnel floor can be kept sanitarily clean and the construction will meet the strongest requirements in regard to fireproofness.

In Figs. 2 and 3 is the drain system indicated. F is 91 a longitudinal pipe and from both sides of the roadway as well as from the area between the rails are branch pipes leading to F. as shown in dotted lines in Fig. 3.

If the open field standard with cross ties about 24 inches on centers is applied in a tunnel about 10 inches 95 broken stone is required under the cross ties if proper tamping shall be done and if the surface of the concrete floor as well as the broken stone proper shall be sayed from crumbling.

The abolition of the ballast and adoption of this track 100 construction means 9 to 10 inches saved in heights of walls and columns and probably in diameter of tunnel or say from 1 to 2 per cent. of the total cost of the structure, not figuring on the easier crossing over sewers etc., which sometimes is of great value.

Splices of rails and rail channels will not present any difficulties. Creeping of rails can be effectively prevented.

The join-timber surrounded by asphalt and the upper face creosoted or tarred will last for 20 years and more. Screw spikes of different diameters but of the same pitch should be kept. When one screw does not draw sufficiently another of larger diameter is driven. Tie plates can be omitted on account of the rails having a larger bearing area.

A suitable side pressure between the screw spike and the rail foot can be secured by attaching a guide for the borer to the rail and by letting the borer run through this guide the spike holes and consequently the spikes proper will be given a constant and suitable position in relation to the rail foot. Finally abandoned screw holes should be filled with a suitable material in order 15 to keep out the water.

After having described my invention what I claim and desire to secure by Letters Patent of the United States, is—

A foundation or bearing for railway rails consisting of a combination of a metal channel C embedded in the sense of a trough in the tunnel or railway floor A of concrete blocks E of wood laid down in said trough and a material D cast into and filling the space between the individual blocks as well as between the blocks and the inner face of the metal channel; all as substantially set forth. 20

In testimony thereof I affix my signature in the presence of two witnesses.

THOMAS M. K. OVERLAND.
